TRANSMITTING APPARATUS FOR ELECTRIC TELEGRAPHS AND THE LIKE.

1,258,809.

Specification of Letters Patent. Patented Mar. 12, 1918.

Application filed October 18, 1913. Serial No. 796,006.

To all whom it may concern:

Be it known that I, LOUIS MAXWELL POTTS, a citizen of the United States, residing at the city of Baltimore and State of Maryland, have invented certain new and useful Improvements in Transmitting Apparatus for Electric Telegraphs and the like, of which the following is a specification.

The primary object of this invention is to provide a keyboard controlled transmitter for telegraph circuits, which will permit the operator to operate the keyboard at an irregular rate or even stop operating altogether for a considerable interval, and yet permit a uniform rate of line transmission, and this without the use of a perforated tape.

In my machine, the keyboard is perfectly free and does not require a lock as is the case with all multiplex systems and most other machine systems which use keyboard transmission. The operation of the keyboard in my machine is, therefore, as free as in an ordinary typewriter.

Moreover, with my machine the operator may stop for a considerable length of time for the purpose of reading and arranging copy, checking off and marking messages, without interfering with the rate of line transmission. This has heretofore been a rather serious difficulty in the case of direct keyboard transmission.

In the Morse system the operator can transmit with one hand, while marking or checking off with the other hand the message previously sent, but with a keyboard this is not practicable, since both hands should be occupied to get the required speed.

It is possible with my machine to so regulate the rate of line transmission that the operator will be able to keep the line entirely busy and thereby lose no line capacity.

My machine has the further advantage that errors of keyboard operation can be corrected before transmission. In the case of the depression of a wrong key, the combination of code elements set up can be replaced and reset correctly before actual transmission takes place.

My machine possesses an economical advantage over tape transmitting systems in that the cost of the tape is saved, and the apparatus is simpler.

While the primary object of this invention is as above stated, it is applicable to various

other uses, all within the scope of my invention as set forth in the accompanying claims.

In order that my invention may be better understood, I shall now describe a specific embodiment thereof in detail, to accompany the drawings wherein:

Figure 1, is a top plan view of one form of machine embodying my invention, with a portion of the keyboard broken away:

Fig. 2, a vertical sectional elevation thereof;

Fig. 3, a detail side elevation of the spacing contact mechanism;

Fig. 4, a detail front elevation of said contact mechanism with the combination bars which actuate it shown in section;

Fig. 5, a detail vertical section of the transmitter carriage;

Fig. 6, enlarged detail perspective views of two of the transmitting contact operating levers;

Fig. 7, a diagram illustrating one form of code which may be used with my machine;

Figs. 8 to 11, inclusive, detail views showing the operation of setting the contact operating pins and returning them to normal, and

Figs. 12 and 13, diagrams of the electrical circuits and connections.

The machine herein shown comprises, among other parts, a frame 1, on which is fulcrumed a series of key levers 2, provided with keys 3, arranged after the fashion of the standard typewriter keyboard, and each of these keys adjacent its rear end has a beveled upper edge 4.

Extending transversely across all said key levers and lying above the beveled portions 4 thereof, is a series of eight longitudinally slidable combination bars 5, supported near each end upon pins 6 passing through slots 7 in said levers and mounted between plates 8 and 9 secured fast to the machine frame, said plates being slotted as at 10 to act as guides for the key levers. Each of these combination bars is provided on its lower edge with a series of cam faces 11 slanting upward from right to left, and adapted to be engaged by the beveled edges 4 of the key levers when the latter are operated. These cams are arranged on the lower edges of said combination bars in accordance with the code employed, so that the operation of

each key lever shifts a certain one or combination of these bars to the right, Fig. 1. The operation of combination bars in this manner, however, is old and well known in the art, so need not here be further described. (See, for example, United States Patent No. 1,105,920.)

In addition to the cam faces 11, the combination bars may be provided with a series 10 of cam faces 12 slanting upward from left to right, and so arranged that when a given combination bar is shifted, as above described, these cams will occupy such position above the unoperated key levers as to prevent the operation of two keys at once. Nothing new, however, is here claimed for this arrangement.

Each combination bar has on its upper edge a cam 13, and each of these cams is 20 in operative relation, respectively, with one of a series of eight levers 14. These levers are in turn in operative relation with eight vertically slideable rods 15, the lower extremities of which lie directly above levers 14, 25 near their free ends. The rods 15 are guided vertically by a plate 16 and a bracket 17 through which they pass, said rods resting by means of shoulders 18 upon said bracket, and shoulders 19 upon plate 16. Supporting some of the rods on shoulders 19 and others on shoulders 18 is merely for the purpose of allowing room for said shoulders.

The upper ends of rods 15 lie, respectively, beneath upturned ends of eight levers 20, the tails of which levers are wedge shaped as at 21, where they separate, as later described, with a knife edge 22 secured to an arm 23 pivoted as at 24 (see Fig. 1), and operatively connected to a rod 40 25 adapted to be operated by a plunger magnet 26.

Fast upon stationary brackets 27, mounted on the top plate 16 of the machine frame, is a circular plate 28 having an annular 45 circular recess 29 (Fig. 2) forming a flange 30. Adapted to rotate within this recess and supported upon the said flange is a flat ring 31.

This ring 31 carries adjacent its inner 50 edge a series of equally spaced pins 32 fast thereto and extending entirely around the ring. These pins engage with the teeth of a sprocket 33 rotatable upon a pivot 34 fast to the machine frame. Fastened rigidly to this sprocket and rotatable about a common axis therewith, is a ratchet 35 with which is adapted to engage a pawl 36, pivoted upon an arm 37, which in turn is pivoted upon the axis of said ratchet. Arm 37 is normally held against an adjustable stop 38 by a strong spring 39, and its movement away from said stop is limited by an adjustable stop 40. This arm 37 is in operative relation with plunger rod 25, so that the operation of magnet 26 acting through said rod

will force arm 37 against the tension of spring 39, and allow pawl 36 to step back a tooth on a ratchet 35, and when magnet 26 is deenergized, spring 39 will return arm 37, and in doing so cause pawl 36 to advance 70 its ratchet a certain distance, which will, acting through sprocket 33 and pins 32, rotate ring 31 in a clockwise direction one step, the distance of which will be hereinafter more particularly referred to.

Extending transversely through ring 31, and slidable friction tight therein, are a multiplicity of groups of permutation elements in the form of pins 41, eight pins in each group, and said groups arranged in 80 straight lines radiating from the central axis of ring 31.

In actual practice, the machine herein described has 216 such groups of pins, but in the drawings a few only of these are shown, 85 it being understood that these groups of pins extend entirely around the ring 31, or as far around the same as desired. These groups of pins are equally spaced apart, and corresponding pins of the several groups lie 90 in eight circles struck from the center of ring 31.

Pins 41 are adapted to come into alignment, respectively, with the upturned ends of the eight levers 20 and to be operated thereby as later described. The function of these pins is to operate in various combinations a series of movable transmitting contacts 42. These contacts, each of which comprises a small spring, are mounted suitably 100 insulated from each other upon a transmitting head or contact carriage 43. Contacts 42 are adapted to move between and alternately engage relatively stationary pairs of contacts 44 and 45 also mounted 105 upon said carriage (see Fig. 5). These relatively stationary contacts are mounted upon metal supports 46, 47 and 48, insulated from each other and from the other parts of the frame of the carriage.

Contacts 42 are adapted to be operated by pins 41 through the medium of eight levers 49 fulcrumed on a common support 50 on the contact carriage (see Fig. 5). One-half of these levers have straight ends 51, and the other half hooked ends 52. The contacts 42 are arranged in two groups of four each, and the levers having straight ends 51 are adapted to operate four of these contacts, and the levers having hooked ends are 120 adapted to operate the other four of said contacts, the straight ends 51 of said levers acting to push their said contacts, and the hooked ends adapted to pull their contacts in operation, since the upper ends of levers 125 49 all move in the same direction in being operated by pins 41. The levers 49 have insulated tips 53 (Fig. 8), so that they do not make electrical connection with spring contacts 42. Each lever 49 termi- 130

nates at its lower end in a downwardly extending finger 54 and the levers are so spaced that these fingers travel, respectively, in the paths of the pins 41; that is, in the travel of the contact carriage, the fingers 54 traveling in the eight circles in which the pins 41 are arranged.

The lower portion of each lever 49, in its normal position abuts against a stop 55.

10 (See Fig. 5.)

The transmitting contact carriage is mounted upon the outer end of an arm 56, fast to a sleeve 57, which is rotatable and vertically movable on a stud 58 fastened 15 rigidly to the machine frame.

Arm 56 is normally held up so that the lower extremities of the levers 49 clear pins 41 when the latter are pushed up, and this is effected by means of a spring 59 acting 20 through a magnet armature 60, having a yoke 61 adapted to engage with two annular flanges 62 on sleeve 57.

An electro-magnet 63 made fast to the frame of the machine is adapted to operate 25 armature 60, and when this magnet is energized, as hereinafter described, it will act through said armature to lower arm 56, and thereby bring the fingers on the lower ends of levers 49 into position to be engaged 30 by pins 41.

Arm 56 carries a bell crank lever 64 fulcrumed thereon at 65, and having an arm extending over the upper edge of stud 58, through an opening 66 in sleeve 57. The 35 other end of this bell crank lever is pivotally connected to a link 67, which link is in turn pivotally connected to an arm 68. This arm is fast to a spindle 69 mounted to rotate in a bracket 70 fast to arm 56. Also 40 fast to spindle 69 is an escapement pawl 71, which is adapted to engage with the teeth of a ratchet 72, mounted for rotation on arm bracket 70. Rigidly secured to this ratchet and adapted to rotate on the same 45 axis therewith is a sprocket 73, the teeth of which are adapted to engage with pins 32 on the ring 31.

The movement of link 67 to the right, Fig. 2, is against the tension of a spring 74, 50 secured at one end to a pin 75 on arm 56, and at its other end to a pin 76 on link 67.

Arm 56 is under tension horizontally of a spring 77 through a cord 78 attached at one end to a drum 79, and at its other to 55 the sleeve 57.

The spring 77 may be unwound by the operation of an escapement pawl 80, on a ratchet 81, fast to the winding shaft of said spring.

60 After pins 41 have been set and have operated upon the contact levers 49, they must be returned to normal before they again reach the setting point. This is accomplished by means of a lever 82 having a 65 transverse extension 83 adapted to extend

over one row of pins 41 and normally just above the tops of said pins when they protrude through the ring 31 in their set positions. This lever is pivotally mounted upon a stud 84 carried by a bracket 85 fast on 70 the machine frame. The end of lever 82 opposite extension 83 has a beveled edge 86 (see Figs. 8 and 10) adapted to engage with knife edge 22. When said knife edge 75 engages the beveled end of lever 82, its extension 83 is forced downward upon and returns to normal any pins which may have been set.

Each combination bar also carries on its upper edge a pin 87 (see Figs. 3 and 4), 80 the function of which is to operate a spacing contact each time one or more of said bars is slid forward. The mechanism by which these pins thus operate the spacing contact comprises, among other parts, a 85 pivoted yoke 88, straddling all of said combination bars, and lying directly in front of pins 87, and adapted to be rocked on its pivots by the operation of any of said combination bars. This yoke is adapted, 90 when so rocked, to operate through a pin 89 thereon a downwardly extending arm of a bell crank lever 90, fulcrumed on a bracket 91 secured to a block of insulation 92 fast to the machine frame. The other arm of 95 this lever is adapted to operate upon a contact spring 93, made fast to insulating block 92. This spring carries a contact 94, which is adapted at times to engage with an adjustable contact 95, mounted upon an arm 100 96, secured to block 92. Lever 90 operates contact spring 93 through an insulating tip 97.

In Fig. 7, I have indicated diagrammatically one form of code which may be employed with my machine, said diagram showing the various combinations in which the pins 41 may be operated to form the different signals. In this diagram the vertical row of dots indicated *a*, *b*, *c*, *d*, *e*, *f*, and 105 *h*, represent the row of pins 41, and the dots beneath each of the characters along the top of the diagram indicate the combinations in which the pins are operated to transmit signals corresponding to these characters. The 110 dots beneath the three blank spaces between zero and the character "&" represent the combinations in which the pins are operated for sending signals for forming certain operations when these signals are used for operating a page printing machine to effect the lining, spacing, and backing of the carriage, but since such apparatus forms no part of this invention, further description along this 115 line is considered unnecessary. The pins 41 120 may be operated in these combinations for any other desired purpose.

From this diagram may also be obtained the positions of the combination operating cams 11, on all of the combination bars 5. 125 130

These combination bars correspond, respectively, to horizontal lines opposite the vertical row of characters *a* to *h*, and the dots in these horizontal lines, except the vertical 5 row of eight dots at the extreme left hand end of the diagram, indicate the relative positions of the combination cams on these bars.

It should be understood, however, that 10 my invention is in no sense limited to this particular code.

One arrangement of the electrical connections is shown in Fig. 12, where 98 represents in development a segmented transmitting commutator which is in permanent electrical connection with a collector ring 99 through electrically connected brushes 100 and 101, which we may assume are driven by any suitable mechanism. Collector ring 20 99 connects to telegraph line 102, while the eight segments of commutator 98 are electrically connected respectively to movable transmitter contacts 42. Alternate front and back stationary contacts 44 and 45 are connected to positive and negative of a source of current supply 103, grounded as shown. This arrangement of electrical connections is old and well known in the art, and is not here claimed as new in itself; that is, considering contacts 42, 44, and 45, merely as electrical contacts, aside from their relation to the improved transmitting mechanism herein shown and described. As brushes 100 and 101 rotate, they transmit to line current 35 impulses from the source 103, depending upon the state of contacts 42. If all of these contacts occupy the same relative positions, as shown in Fig. 12, alternate plus and minus impulses will be transmitted to line as the 40 brush 100 sweeps the segments of commutator 98 connected to said contacts. The signals are transmitted by moving contacts 42 from the positions shown in Fig. 12 to their opposite contacts in various combinations, 45 thus transmitting to line impulses reversed in polarity from the normal. This in itself is an old method of transmission, and need not be further described.

Adapted to travel with the brushes 100 and 101 are other electrically connected brushes 104 and 105, which sweep contact rings 106 and 107, respectively, said rings being shown in development. The ring 106 contains a segment 108, somewhat greater in 55 length than the space occupied by the eight narrow segments of the commutator 98, and this segment 108 is permanently electrically connected to a terminal of magnet 63. The other terminal of this magnet connects, 60 through a suitable resistance 109, with a positive main 110 leading from a local source of direct current. The collector ring 107 is permanently electrically connected to the negative main 111 from said direct current 65 source. This negative main is also connect-

ed, through spaced contacts 94 and 95, with a terminal of plunger magnet 26, the other terminal of which connects through suitable resistance 112 to positive main 110.

Assuming the electrical connections to be 70 as in Fig. 12, the operation of my improved transmitter is as follows:

The depression of a key 3 moves a certain one or combination of bars 5 to the right as the operator faces the machine, and these 75 in turn, acting through cams 13, move corresponding combinations of levers 14 upward, and these in turn acting through rods 15, send the heads of levers 20 upward in corresponding combinations. These levers 80 20, however, at this time only move sufficiently far for their tails 21 to come below the knife edge 22.

The depression of any key causes the combination bars 5, acting through pins 87 and 85 yoke 88, to close the space contacts 94 and 95, thus energizing magnet 26. This magnet will then push the rod 25 outward, and, acting through arm 23, will cause the knife edge 22 to move toward the tails of levers 90 20, engaging the upper beveled faces of said tails and causing the heads of said levers to rise still farther in the same direction in which they were moved by the rods 15. Knife edge 22 passes over the tips of the 95 set levers 20 and under the tips of those of said levers which are unset, or which do not enter a given signal combination, thus locking all said levers against further operation until knife edge 22 returns to normal, 100 consequently preventing interference with the combination of pins already set by premature depression of another key. The heads of levers 20 in thus rising, will push corresponding pins 41 upward and cause the 105 same to project above the upper face of ring 31. When pressure is released from the operated key, the operated combination bars 5 return to normal by yoke 88 and spring 93, and contacts 94 and 95 separate, thus de-energizing magnet 26. When magnet 26 becomes thus deenergized, spring 39, acting through arm 37, pawl 36, and ratchet 35, will cause the sprocket wheel 33 to rotate the ring 31 in the direction of the larger 115 arrow Fig. 1, or in a clockwise direction, the distance of one space; that is, the distance of one radial line of pins 41 to the next, thus bringing a new line of pins in the setting position. The ring 31 thus rotating carries the arm 56 along with it, the angular relation of this arm to said ring always remaining the same, independent of the operation of magnet 26, provided magnet 63 is not operating, or in other words, 120 when not transmitting. Arm 56 in being thus moved, winds up the spring 77.

Magnet 63 is energized at regular intervals, as brush 104 sweeps segment 108, and each time so energized will cause sleeve 57 130

and arm 56 to descend, at which time stud 58, acting through bell crank 64, sends link 67 to the right, Fig. 2, and in so doing lifts pawl 71 out of the teeth of ratchet 72 and 5 allows spring 77 to rotate arm 56 a fractional part of a step in the direction of the smaller arrow Fig. 1. As the brush 104 passes from segment 108, spring 59 causes sleeve 57 to rise. This permits the spring 10 74 to pull arm 67 to the left, Fig. 2, thus causing pawl 71 to again engage ratchet 72 and lock the arm 56 against movement relative to ring 31 until the magnet 63 is again energized. In its step-by-step motion, arm 15 56 travels a fractional part of a step when it descends and completes the step when it rises.

If, when arm 56 is rotated one step in the counter-clockwise direction indicated by the 20 smaller arrow, Fig. 1, as above described, there are any pins 41 protruding above the upper face of ring 31, these will be engaged by the lower ends or fingers of contact levers 49, whereupon the said levers will be rotated on their axes and the corresponding 25 contacts 42 operated.

Magnet 63 remains energized during the 30 whole time that brush 104 passes over segment 108, so that the transmitting contacts are set during the entire time of transmission. When magnet 63 becomes deenergized, arm 56 is raised by spring 59, and pawl 71 falls into the next tooth of ratchet 72, and said arm is advanced another space 35 and is in position to transmit the next signal. In other words, after each transmission, the lower ends of transmitting levers 49 leap over the pins 41, which had previously operated them, into position to be 40 operated by the next adjacent row of pins.

As the pins 41 come successively over the extension 83 of lever 82, they are returned to normal as hereinbefore described.

It will be seen from the foregoing 45 description that the operation of setting the combinations is entirely independent of the operation of transmitting, so that either one may be taking place independently of the other, or both together at the same rate or 50 at different rates. The operator merely sets the signals. The machine stores them and automatically transmits them. The ring 31 is made of such size that the operator will be allowed ample time for any ordinary delays or interruptions. As hereinbefore stated, this ring contains, in the machine herein described, 216 sets of pins 41, and allowing for six characters to a word, this means that the said ring will contain about 60 thirty six words, so that if the operator worked faster than the transmission and completely filled the ring with signals to be transmitted, and the transmission were at the rate of thirty six words per minute, the 65 operator could then be idle for a whole

minute at a time without impairing the line efficiency.

For the purpose of insuring the completion of the operation of setting up a signal on ring 31, there is provided, among 70 other parts, a polarized relay 113 having the terminal of its forward coil connected in series with space contacts 94 and 95, and thence to an insulated spring contact 114 of switch 115 operated as hereinafter described. 75 by magnet 26.

The back coil terminal of relay 113 is connected to another insulated spring contact 116 of said switch, while both coils receive current from a conductor 117 tapped 80 on to the coil circuit of said relay at 118 and connected to the positive main 110 through a suitable resistance 119.

Switch 115 is provided with an intermediate spring contact 120 adapted to move 85 between and alternately engage contacts 114 and 116, but normally held under tension against contact 114 by an insulating stop 121 fast on the plunger rod 25.

The forward contact 122 and tongue of 90 relay 113 are in series with the coils of magnet 26 from the local supply mains 110 and 111, in which circuit is also connected a suitable resistance 123.

By this arrangement, if a key be operated 95 only sufficiently to close space contacts 94, 95, the front coil of relay 113 will receive current through normally closed switch contacts 114 and 120, and will close its forward contact 122, thereby energizing magnet 100 26, whereupon said magnet will push its plunger 25 the limit of its motion, since the tongue of relay 113 will not return until contact 120 engages contact 116.

The tongue of relay 113 is returned to its 105 back stop on the closure of contacts 116 and 120.

For the purpose of automatically stopping the travel of arm 56 and thereby stopping the setting of contacts 42, when the 110 transmission has caught up with the setting operation, that is when the transmitting carriage has gotten around to a point where it transmits the signals immediately set up, there is provided, among other parts, a 115 switch 124 having two insulated spring contacts 125, and 126 secured to the machine frame and so located that when the transmitting carriage has reached a certain part, an insulated finger 127 thereon will 120 strike a projection of contact spring 125 and open said switch.

Contact spring 126 of this switch is electrically connected through a hand operated switch 128 to a terminal of the forward coil 125 of a polarized relay 129, while contact spring 125 is electrically connected to an insulated segment 130 in ring 131 which takes the place of ring 106.

Segment 130 is so located that brush 130

104 will arrive on it just before brush 100 reaches the first segment in ring 98. Another insulated segment 132 in ring 131 is electrically connected to a terminal of 5 the back coil of relay 129, and is so located that brush 104 will engage it just after brush 100 passes the last of the group of transmitting segments in ring 98.

Between the front and back coils of relay 10 129, the magnet coil circuit of the relay is tapped by a conductor 133 which connects through a suitable resistance 134 with the positive current supply main 110.

The tongue of relay 129 is connected to 15 negative main 111, and the forward contact of said relay is connected through coils of magnet 63 and a resistance 135 with the positive main.

Relay 129 is employed in order to prevent 20 the opening of switch contacts 125, 126, from interfering with the transmission of a signal already started. If the circuit of magnet 63 were opened by switch 124 directly, this might occur in the middle of a 25 signal and consequently cause an error. Since the relay 129 cannot act to either open or close the circuit of magnet 63, except just before or just after a signal interval, owing to the disposition of segments 130 and 132, 30 the signal will either be transmitted completely or not at all.

As long as switch 124 remains closed, magnet 63 is energized once on each revolution of brushes 104, 105, as brush 104 engages 35 segment 130, and the tongue of relay 129 is returned to its back stop on every revolution of said brushes as brush 104 engages segment 132.

When finger 127 on the transmitting carriage 40 engages extension of spring contact 125, however, the circuit of the forward coil of relay 129 will be broken, so that transmission will be automatically stopped.

When the transmission has caught up 45 with the setting operation, that is, when the transmitting carriage has gotten around to a point where it transmits the signals immediately set up, and the keyboard operator desires to get a lead on the transmission, he 50 may open hand switch 128, and continue the operation of the keyboard. Opening switch 128 breaks the circuit of magnet 63 and therefore stops transmission. When the operator has stored up the desired quantity of 55 signals he may then close switch 128, when the transmission will be resumed.

The rotary distributing device or sunflower, which actually times the transmission, is in many of the claims denominated 60 a master transmitter.

Having now described in detail certain specific apparatus embodying my invention, it should be understood that this is susceptible to considerable modification without exceeding the scope of my claims.

What I claim is:

1. Transmitting apparatus for electric telegraphs, comprising a series of movable elements, mechanism for setting said elements according to the signal to be transmitted, electrical signal transmitting means controlled by said elements, and means having a uniform movement and acting independently of said movable elements at regular intervals to time the operation of said transmitting means, the operation of said element setting mechanism and said timing means being mutually independent. 70

2. Transmitting apparatus for electric telegraphs, comprising a series of groups of 80 movable elements, mechanism for setting said elements in code combinations according to the signal to be transmitted, signal transmitting means, and automatically acting means to effect relative motion between 85 successive groups of said elements and said transmitting means to operate the latter, the combination of elements set for any given signal acting upon said transmitting means simultaneously. 90

3. Transmitting apparatus for electric telegraphs, comprising a series of groups of movable elements, mechanism for setting said elements in code combinations corresponding to the respective signals to be 95 transmitted, signal transmitting means, key controlled mechanism adapted to bring said groups of elements successively into operative relation with said setting mechanism, and electrically controlled means to effect relative step-by-step motion between said elements and said transmitting mechanism to operate the latter, the timing of the operation for said setting mechanism and said electrically operated means being mutually 100 independent. 105

4. Transmitting apparatus for electric telegraphs, comprising a series of groups of movable elements, a common support therefor, mechanism to set said elements of the 110 respective groups in code formation corresponding each to a combination of impulses forming an individual character signal, a second support relatively movable with respect to the first mentioned support, a group of 115 elements movably mounted on said second support, means to bring the elements upon the two relatively movable supports into operative relation, and signal transmitting means operated by the conjoint action of the elements on the two said relatively movable supports. 120

5. Transmitting apparatus for electric telegraphs, comprising a series of groups of 125 movable elements, a common support therefor, key controlled power operated mechanism to set said elements of the respective groups in code formation, a second support relatively movable with respect to the first mentioned support, a group of elements 130

cessively into operative position to be set, and signal transmitting means operated by said elements when set.

15. Transmitting apparatus for electric telegraphs, comprising a series of groups of movable elements, mechanism for setting said elements according to the signal to be transmitted, signal transmitting means, power means to effect relative motion between successive groups of said elements and said transmitting means to operate the latter, and periodically operating electrical means acting only after impulses corresponding to a complete signal have been transmitted and before the first impulse for a succeeding signal has been transmitted to effect the operation of said power means.

16. Transmitting apparatus for electric telegraphs, comprising a series of movable elements, mechanism for setting said elements in code combinations according to the signal to be transmitted, signal transmitting mechanism, means to effect relative motion between said elements and said transmitting mechanism to operate the latter from said elements, and means operative at will to stop the operation of said transmitting means by said elements independently of the operation of said element setting means.

30 17. Transmitting apparatus for electric telegraphs, comprising a series of movable elements, mechanism for setting said elements in combinations corresponding to a combination of impulses representing the signal to be transmitted, electrical signal transmitting means controlled by said elements, means comprising a member having a uniform movement independent of said elements and acting at regular intervals, to time the operation of said transmitting means, the operation of said element setting mechanism and the said means being mutually independent, and means to automatically restore said elements to normal.

45 18. Transmitting apparatus for electric telegraphs, comprising a rotatably mounted plate, a series of groups of elements movably mounted on said plate and arranged to travel in a circular path, a keyboard, selective mechanism operated by said keyboard to set said elements in accordance with the signal to be transmitted, mechanism including an electro-magnet to impart step-by-step rotary motion to said plate, a contact carrying carriage, an angularly movable support for said carriage, means including a spring under tension tending to move said carriage support counter to the movement of said plate to bring said contacts into operative relation with said groups of elements successively, an electro-magnet, an escapement co-operating with said spring to operate said carriage support, and means to periodically energize said magnet.

60 19. Transmitting apparatus for electric

telegraphs, comprising a series of groups of signal controlling elements, mechanism to selectively operate said elements according to the signal to be transmitted, means controlled by said elements for transmitting electrical signal impulses, a magnet also controlling said signal transmitting means, and means operating said magnet only after impulses corresponding to a complete signal have been transmitted and before the first impulse for a succeeding signal has been transmitted.

70 20. Transmitting apparatus for electric telegraphs, comprising a series of groups of movable elements, means operative upon successive groups of said elements to set them in varying code combinations, each combination corresponding to a signal to be subsequently transmitted, a group of movable elements corresponding in number to 80 those constituting the individual groups of the first mentioned elements, means controlled by the first mentioned elements, one group at a time, to arrange the second mentioned elements in successive code formations corresponding to the arrangement of the elements in the respective groups of the first mentioned elements, means to render said arranging means operative only in the intervals between the transmission of successive signals, and means to operate said element setting means independently of the control of the second mentioned elements by the first mentioned elements.

85 21. Transmitting apparatus for electric telegraphs, comprising a series of movable elements, mechanism for setting said elements according to the signals to be transmitted, electrical signal transmitting means controlled by said elements, and electrical 105 means comprising a switch acting only after impulses corresponding to a complete signal have been transmitted and before the first impulse of a succeeding signal has been transmitted to effect relative movement between said transmitting means and said elements.

110 22. Transmitting apparatus for electric telegraphs, comprising a series of groups of movable elements, a keyboard, mechanism 115 forming operative connection between the keys of said keyboard and the said elements for operating elements of each group in code combinations corresponding to the signal to be transmitted, a group of transmitting elements, means to bring said groups of transmitting elements into engagement with said groups of movable elements and so set said transmitting elements in said combinations, and means acting subsequently to transmit 120 the signal.

125 23. Transmitting apparatus for electric telegraphs, comprising a series of movable elements, mechanism for setting said elements in code combinations corresponding to 130

- movably mounted on said second support, automatic means to bring the elements upon the two relatively movable supports into operative relation, and signal transmitting means operated by the conjoint action of the elements on the two said relatively movable supports.
6. Transmitting apparatus for electric telegraphs, comprising a keyboard, permutation mechanism operated thereby, a series of groups of movable elements, means controlled by said permutation mechanism to set said elements in the individual groups in various combinations, a common support for all said elements, means controlled by said keyboard to effect relative motion between said support and said element setting means, a series of members corresponding in number to the elements in each of said groups, a carriage supporting said members, mechanism to effect relative motion between said support and carriage to bring the members on said carriage into operative relation with successive groups of elements carried by said common support, and electrical signaling transmitting means operated by said members.
7. Transmitting apparatus for electric telegraphs, comprising a movable supporting member, a series of groups of elements movably mounted on said member, the number of said elements in each group being the same and corresponding respectively to impulse periods allotted the respective signals, a keyboard, mechanism forming operative connection between said keyboard and elements to set said elements in the respective groups in code combinations corresponding to the impulses which go to form given signals, a series of contact operating members adapted to be operated by said elements when set, and mechanism for effecting relative step-by-step movement between said movable supporting member and said contact operating members to effect the operation of the latter.
8. Transmitting apparatus for electric telegraphs, comprising a series of groups of movable elements, a keyboard, mechanism forming operative connection between the keys of said keyboard and the said elements for operating said groups of elements successively and the elements of each separate group in a code combination corresponding to the signal to be transmitted, signal transmitting means, and means to bring groups of said elements simultaneously into operative relation with said transmitting means.
9. Transmitting apparatus for electric telegraphs, comprising a movable web or plate, a series of groups of pins movably mounted on said plate, a keyboard, mechanism forming operative connection between the keys of said keyboard and the said pins for operating said groups of pins successively and the pins in each group in combinations corresponding to the signal to be transmitted, a series of electrical contacts operated by said pins, a carriage carrying said contacts, and mechanism to move said carriage in an opposite direction to the movement of said web or plate and thereby cause the operation of said contacts by said pins.
10. Transmitting apparatus for electric telegraphs, comprising a movable web or plate, a series of groups of pins movably mounted on said plate, a keyboard, mechanism forming operative connection between the keys of said keyboard and the said pins for operating said groups of pins successively and the pins of each group in combinations corresponding to the signal to be transmitted, a series of electrical contacts, mechanism operated by said pins to operate said contacts, a carriage carrying said contacts and their said operating mechanism, mechanism to move said carriage in an opposite direction to the movement of said web or plate, and electrically controlled means operating independently of the time of operation of said keyboard to control the operation of said carriage operating means.
11. Transmitting apparatus for electric telegraphs, comprising a series of movable elements, mechanism for selecting said elements in code combinations according to the signal to be transmitted, power operated means to operate the elements selected, and means controlled by said elements to transmit the signal selected.
12. Transmitting apparatus for electric telegraphs, comprising a movable web, a series of groups of movable elements mounted in said web, means including permutation mechanism to operate the elements of each separate group in combinations corresponding respectively to individual character signals to be subsequently transmitted, signal transmitting means controlled by said elements, means to effect relative step-by-step motion between said elements and said transmitting means to effect the operation of the latter, and mechanism to automatically stop said movement.
13. Transmitting apparatus for electric telegraphs, comprising a series of transmitting switch contacts, a controller for operating said contacts and movable relative thereto, means including a spring under tension tending constantly to effect said motion, and electrically operated means cooperating with said spring to effect said motion.
14. Transmitting apparatus for electric telegraphs, comprising a series of groups of movable elements, a common support therefor, key controlled mechanism to set said elements according to the signal to be transmitted, an electro-magnet controlled from said keys, mechanism cooperating with said magnet to bring said groups of elements suc-

the respective signals to be transmitted, electric signal transmitting means controlled by said elements, means to bring succeeding elements into operative relation with said transmitting means, and means acting after 5 said elements have been brought into operative relation with said transmitting means, to time the signals.

24. Transmitting apparatus for electric 10 telegraphs, comprising a magazine having a plurality of members movably mounted therein and operable at an arbitrary rate as compared with that of the line transmission to store up in said magazine signals to be 15 subsequently transmitted, circuit controlling means, and a member having a uniform movement and acting to effect coaction at regular intervals between said signal storage members and said circuit controlling means.

20 25. Transmitting apparatus for electric telegraphs comprising a magazine having a plurality of members movably mounted therein and operable at an arbitrary rate as compared with that of the line transmission to store up in said magazine signals to be 25 subsequently transmitted, circuit controlling means, and means to effect co-action between said storage members and said controlling means at regular intervals, said means including an electric circuit, a contact therein, and means to operate said contact at a uniform rate independent of the rate of operation of said members in storing up the signals.

30 35. 26. Transmitting apparatus for electric telegraphs comprising a main line, a series of branch circuits, a switch contact in each of said branch circuits and means to operate said contacts to connect said branch circuits 40 successively to the main line and at regularly recurring intervals, a second switch contact in each of said branch circuits, a magazine comprising a supporting member and a plurality of impulse selectors movably mounted 45 thereon and adapted to control the operation of said second mentioned contacts, mechanism to effect co-action between said impulse selectors and said second mentioned contacts at regularly recurring intervals, and 50 means operable independently of the rate of operation of said second mentioned contacts, to operate said impulse selectors to store the signals to be subsequently transmitted.

55 27. Transmitting apparatus for electric telegraphs, comprising a magazine having a series of elements movably mounted therein, means to set said elements in code combinations corresponding to the respective signals to be transmitted, a second series of elements, means to effect relative movement between said two series of elements to effect 60 operation of the second series by the first series in combinations corresponding to the elements set in the first series, means to render said second series of elements inopera-

tive by the movement of the first series at will and independently of the operation of setting the first series, and signal transmitting means controlled by said second series of elements.

70

28. Transmitting apparatus for electric telegraphs, comprising a magazine having a series of elements movably mounted therein, means to set said elements in combinations corresponding to the respective signals to be 75 transmitted, a second series of elements, means to effect relative movement between said two series of elements to effect operation of the second series by the first series in combinations corresponding to the elements set in the first series, means to render said second series of elements inoperative by the movement of the first series at will and independently of the operation of setting the first series, but only after the complete 80 signal corresponding to the combination already set has been transmitted, and signal transmitting means controlled by said second series of elements.

80

29. In a telegraph transmitter, a movable carrier, groups of circuit controllers carried thereby, keyboard selecting mechanism to set the circuit controllers in transmitting position, a transmitting head carrying a group of circuit closers and means to bring 90 into engagement said groups of circuit closers with successive groups of circuit controllers, a master transmitter comprising contact devices separately connected to the circuit closers for transmitting impulses 100 therefrom to the line in substantially regular succession.

90

30. In a telegraph transmitter, a movable carrier, groups of adjustable circuit controllers carried thereby, a keyboard selecting mechanism to set the circuit controllers in transmitting position, means for driving the movable carrier step by step, a transmitting head carrying circuit closers, said circuit closers engaging with successive 105 groups of circuit controllers, and a master transmitter comprising contact devices separately connected to the said circuit closers to successively transmit impulses therefrom, and means to control the action of the transmitting head from the master transmitter.

105

31. In a telegraph transmitter, a movable carrier, groups of circuit controllers carried thereby, a keyboard selecting mechanism to set the circuit controllers in transmitting 110 position, an electromagnet, and mechanism operated by said electromagnet to advance the carrier equal distances, the circuit of said electromagnet being controlled from the keyboard.

110

32. In a telegraph transmitter, a movable carrier, groups of circuit controllers carried thereby, a keyboard selecting mechanism to set the circuit controllers in transmitting 115 position, said keyboard including a univer-

115

sal bar, a feed mechanism operated by an electromagnet to advance the movable carrier equal distances, and a circuit closer operated by said universal bar included in the 5 circuit of the said electromagnet.

33. In a telegraph transmitter, a movable carrier, groups of circuit controllers carried thereby, a keyboard selecting mechanism to set the circuit controllers in transmitting 10 position, a feed mechanism to advance the movable carrier equal distances after a group of circuit controllers have been set in transmitting position, and means for locking the movable carrier against movement 15 in either direction when the feed mechanism is at rest.

34. In a telegraph transmitter, a movable carrier, circuit controllers arranged in groups of unit length supported on said carrier, a transmitting head having circuit closers equal in number to the controllers in a group, means for advancing said head into engagement with said controllers when the latter are at rest, and to hold said head in 20 its advanced position until the impulses corresponding to the group of set controllers have been transmitted.

35. In a telegraph transmitter, a movable carrier, circuit controllers carried thereby, 30 a keyboard selecting mechanism to set the circuit controllers in transmitting position, and a depressing shoe operated from the keyboard to restore the circuit controllers to non-transmitting position.

36. In a telegraph transmitter, a movable carrier, circuit controllers carried thereby, a keyboard selecting mechanism to set the circuit controllers in transmitting position, a transmitting head comprising a group of 40 circuit closers, an electro-magnet to bring said circuit closers into engagement with the circuit controllers, a master transmitter comprising contact devices, said contact devices connected individually to the circuit closers, 45 and a contact operated by the master transmitter to control the action of said magnet.

37. In a telegraph transmitter, a movable carrier, circuit controllers carried thereby, a keyboard selecting mechanism to set the 50 circuit controllers in transmitting position, a transmitting head carrying a group of circuit closers, a magnet to bring said circuit closers into engagement with successive groups of circuit controllers, a circuit 55 breaker included in the circuit of said electro-magnet, and means to control said circuit breaker by the transmitting head.

38. In a telegraph transmitter, a movable carrier, adjustable circuit controllers carried 60 thereby, a keyboard selecting mecha-

nism to set the circuit controllers in transmitting position, means controlled by the keyboard to advance the movable carrier equal distances, a transmitting head carrying a group of circuit closers to operate in 65 conjunction with the circuit controllers, a master transmitter, means controlled by said master transmitter to bring the circuit closers into engagement with successive groups of circuit controllers, and means operated 70 by the position of the transmitting head relative to the movable carrier to control the action of the master transmitter on the transmitting head.

39. A magazine transmitter for electric 75 telegraphs, comprising a storage member, a series of groups of permutation elements movably mounted thereon, mechanism to set said permutation elements in the respective groups in code combinations, a transmitting 80 head having a series of contact controlling members one for each of said permutation elements in a group, mechanism to advance said storage member to bring successive groups of said permutation elements into 85 operative relation with said setting mechanism, and mechanism to move said transmitting head in an opposite direction to the movement of said storage member to bring said contact controlling elements into operative relation with successive groups of said permutation elements to cause the set permutation elements to act upon corresponding contact controlling members to determine the transmission of the signal. 95

40. Transmitting apparatus for electric telegraphs, comprising a magazine having a series of elements mounted thereon, means to set said elements according to the respective signals to be transmitted, means controlled by said elements to transmit electric signals corresponding to the elements set, and means to allot equal time intervals to all the signals. 100

41. Transmitting apparatus for electric 105 telegraphs, comprising a storage member having a series of elements mounted thereon, means to set said elements according to successive signals to be transmitted, a master transmitter adapted to transmit successive 110 signals corresponding to the elements set, and to allot equal time intervals to all the signals.

In testimony whereof I affix my signature in presence of two witnesses.

LOUIS MAXWELL POTTS.
